METHOD AND APPARATUS FOR CASTING

Russell J. Hines, Lakewood, Ohio, assignor to The Hines Flask Company, Cleveland, Ohio, a corporation of Ohio

Application August 11, 1955, Serial No. 527,815

8 Claims. (Cl. 22—27)

This invention relates generally to a method and apparatus for making sand molds for casting and more particularly relates to an improved method and apparatus for simultaneously making more than one sand mold for use in forming a mold cavity.

Ordinarily, sand molds employed in the casting of metals have been made by placing sand in a flask and mechanically pressing or compacting the sand by a pressure board applied to the sand on the side opposite a pattern or pattern board. The mechanical pressing or compacting of the sand may be accomplished by placing the flask in a press having a pair of opposed heads, one of which carries either a cope or a drag pattern plate, and then by moving the press heads together to form the sand mold. Thereafter, the other half of the complete sand mold is made by compressing sand in a flask against the other pattern and the cope and drag flask sections are then assembled with their respective cavities in registration to form a completed mold cavity in which suitable sprue holes and gates are formed in the conventional manner.

Simultaneous production of the cope and drag sections of a mold has been accomplished by using a matched plate having a drag half of a pattern on one side and a cope half of the pattern on the reverse side, after which the plate is attached to a drag flask and used like a follow board when ramming the drag. Thereafter, the matched plate can be left in place and sand rammed in the cope flask against the reverse side of the pattern, after which the matched pattern plate may be removed to leave the cope and drag cavities in registered relation. However, this practice requires uniform thickness of the matched pattern plates in the direction of draw and also requires a high first cost in apparatus and in the procedure of forming a mold. Therefore, it is a principal object of this invention to reduce these requirements by simultaneously forming the cope and drag sections of a sand mold between matched plates carried by opposing heads of a press and thereafter separating the flask sections and reassembling them to form a single mold cavity.

Briefly, the foregoing principal objective of this invention is accomplished by assembling two flasks in surrounding stacked relation on a lower press head carrying a cope pattern plate and with a marginal spacer separating the flasks. The flasks are then filled with sand and the top head of the press carrying the drag pattern plate is swung into place for coaction with the lower head to compress the sand and form the mold sections. Thereafter, the upper head and drag plate are withdrawn, the marginal spacer is removed from between the flasks, and a cutting device is passed between the flasks to cut the sand and to enable the top flask section to be removed from the lower flask section. The flask sections may be then reassembled with their respective cavities in registration to form a completed mold cavity.

In the drawings:

Fig. 1 is a perspective view of a press having a lower and upper head carrying a cope and drag pattern plate

2

respectively between which a pair of flasks are assembled with a marginal spacer between them in accordance with this invention;

Fig. 2 is a perspective view of the marginal spacer; and Fig. 3 is a perspective view of the assembled flasks with the sand molds formed therein and illustrating the marginal spacer partially removed and a cutter ready to be passed between the flasks.

The flasks shown in the drawings embody interconnected wall panels 10 which are hinged together at one corner and which carry a clamp or latch 12 at the other corner for locking the walls together to form a hollow frame open at the bottom and top for surrounding sand on a base or presshead. Each of the flasks is provided with outwardly extending lugs 13 at opposite ends having vertically disposed apertures carrying sleeve like bushings 14 to form guide sockets for receiving vertically extending guide pins 15. The guide pins 15 coact with the guide sockets thus formed to establish and maintain registration of the flask sections during formation of the molds.

Referring now more particularly to Fig. 1 of the drawings, there is shown a mechanical press for pressing or compacting sand in a flask placed between pattern plates carried by a lower head 18 and an upper head 20. The lower head 18 is mounted on the base 17 of the press while the upper head 20 is carried by a swingable arm 19 that can be swung to position the head away from the work space to permit placing and removal of the flasks on the lower head. The lower head is also provided with vertical guide pins like 15 for engagement with the guide sockets in a surrounding flask A to secure the flask in fixed position thereon. A cope pattern plate 16 is mounted on the lower head 18 to form a cope cavity in the sand in the lower flask A. Before locating the upper flask B on the lower flask A, a marginal spacer in the form of a U-shaped metal strip 22 (better illustrated in Fig. 2 of the drawings) is placed on the top edges of the lower flask A. Thereafter, the upper flask B is lowered onto the lower flask and aligned therewith by virtue of the engagement of the vertical guide pins 15 in the corresponding guide sockets formed at the opposite ends of each flask.

The assembled flasks may then be filled with sand to the top of an endless mold reinforcing band 21, and the upper head 20 of the press carrying a drag pattern plate 23 can be swung into place over the upper flask. The sand is compressed in the assembled flasks to form the molds by moving the lower head towards the upper head 20. This may be accomplished by manipulating suitable handles 11 which actuate a conventional lift mechanism in the base. As a result, a cope cavity is formed in the bottom of the lower flask A and a drag cavity is formed on the upper side of the upper flask B and, after the lift is lowered and the upper head removed and swung out of place, the marginal spacing strip 22 can be removed from between the flasks to provide access to the body of sand between the upper and lower flasks.

Fig. 3 of the drawings, shows the spacing strip 22 partially withdrawn with a wire cutting element 25 having a handle 26 at one extremity poised for passage between the flasks. The other extremity may be anchored to the press frame or held by the operator and passage of the wire 25 through the sand between the flasks permits removal of the upper flask B so that it may be placed upon a base board with its drag cavity facing upwardly. Thereafter, the lower flask A can be removed from the press and placed on top of the drag flask with its cope cavity in registration with the drag cavity to form a completed mold cavity. Molten metal may then be poured into this cavity to form a casting.

Thus, it is possible, in accordance with this invention,

to simultaneously form a cope and a drag mold section between opposed press heads carrying matching pattern plates and then separate the mold sections thus formed so that they can be removed from the press and assembled to form a completed mold cavity. This arrangement can be used for either single or multiple molding by properly locating the sprue holes and gates so that a plurality of single mold cavities can be stacked or grouped together to enable their pouring at substantially one operation.

I have shown and described what I consider to be the preferred embodiment of my invention along with suggested modified forms, and it will be obvious to those skilled in the art that other changes and modifications may be made without departing from the scope of my invention as defined by the appended claims.

I claim:

1. The method of forming a complete mold cavity comprising, placing one flask on a pattern plate, locating a spacer member along the top edge of the flask, then placing another flask in registered relation on top of the spacing member, locating another pattern plate above the upper flask, compressing the pattern plates together against sand in the assembled flasks to form matching mold cavities on the top and bottom, removing the spacer member, then separating the upper mold section from the lower by passing a cutting element through the sand in the space formed between the upper and lower flasks, then removing the upper flask from the lower flask and reassembling the flasks with their cavities matching to form a completed mold cavity.

2. An apparatus for simultaneously making multiple sand molds comprising in combination, a press having spaced upper and lower press heads adapted to support a pair of foundry flasks in stacked surmounting relation therebetween and movable towards each other to compress and mold a common body of sand within the flasks, spacing means operably supported between the press heads and adapted to be removably interposed between mating top and bottom edges of stacked flasks for coaction with the press heads to provide access to the compressed body of sand between such stacked flasks, and cutting means carried by the press and adapted to pass through the body of sand between the flasks after removal of the spacing means to separate the upper flask and mold from the lower flask and mold, means for selectively positioning said spacing or said cutting means into operative position between the flasks.

3. The apparatus of claim 2 wherein said cutting means includes a wire element having one end anchored on the press and wherein said positioning means includes, a handle on the free end of said wire element, whereby an operator can grasp the handle and pass the wire element through the sand between the flasks.

4. The apparatus of claim 2 wherein said spacing means includes a frame strip having a configuration corresponding to the edge configuration along all but one edge of the foundry flask, and wherein said positioning means includes an externally accessible portion of said strip to permit retraction of the strip from between the mating edges of the flasks.

5. In an apparatus for simultaneously making multiple matching sand molds the combination comprising, a lower press head having a pattern plate and adapted to support a pair of foundry flasks in stacked surmounting registered relation thereon, an upper press head carrying a matching pattern plate disposed above and adapted for movement toward the lower press head to compress a common mass of sand and form a compound mold within the flasks, a spacer member operably supported between

the press head and adapted for spacing insertion between all but one of the mating top and lower edges of flasks stacked on the lower press head and for coaction with the press heads to provide an accessible body of compressed sand between such flasks, and a wire cutting element operably supported between the press head and adapted to be passed through the body of sand between such flasks after the spacer member is removed and thereby to separate the upper flask and mold from the lower flask and mold, means for selectively positioning said spacing member and said cutting element to operative position between the flasks.

6. A spacer adapted for insertion between a pair of foundry flasks stacked in surmounting registered relation to receive a common body of sand and comprising, a strip of sheet material having a marginal configuration corresponding to the flask boundary and adapted for spacing insertion between mating top and lower edges of stacked flasks, one side of said marginal strip being open to permit unimpeded retraction of the strip from between stacked flasks after they have been filled with a common body of sand, and said strip having a projection adapted to be externally accessible for retraction when the strip is located between the flasks.

7. The strip of claim 6 wherein the material is sheet metal and the marginal configuration is generally U-shaped, and wherein the strip projection includes extensions of the strip portion forming the base of the U-shape beyond either leg in the plane of the strip to provide externally accessible handles.

8. The method of simultaneously forming multiple sand molds adapted to cooperate to form a complete mold cavity comprising, assembling a pair of flasks in spaced surmounting registered relation between a pair of press heads each carrying a pattern plate, compressing sand in the assembled flasks to form matching mold sections by moving the press heads together, then separating the mold sections while the flasks are disposed in surmounting relationship by passing a cutting element through the sand in the space between the flasks to permit reassembly of the flasks with their cavities matching to form a completed mold cavity, said method further characterized wherein the assembling of the flasks includes placing one of the flasks on a base press head, then locating a spacing member along the top marginal edges of the flask, then placing the other flask in registered relation on top of the spacing member, and after compressing sand in the assembled flasks, separating the mold sections by first removing the spacing member and then passing the cutting element through the sand in the space formed by the spacing member between the upper and lower flasks.
